UNITED STATES PATENT OFFICE

MATHIAS FRÄNKEL, OF AUGSBURG, GERMANY, ASSIGNOR TO PHILIPP AUGUST WEYD-MANN, OF VIENNA, AUSTRIA

METALLIC FILLING FOR COLD ACCUMULATORS REISSUED

Application filed July 21, 1928, Serial No. 294,356, and in Germany August 1, 1927.

The object of the present invention is to provide a cold accumulator suitable for use in the process described in patent application, Serial Number 81723, process for separation of gas-mixtures, especially of air, in which the exchange of cold is effected by means of regenerators arranged for reversed operation. The cold accumulator used in this process consists of a cylindrical or square shell of sheet metal through which the air or other gaseous mixture flows in axial direction between a number of strips of sheet metal disposed inside the shell at a distance of from 0,5 to 2,5 mm. apart from one another, whereby an exchange of cold or heat is effected. As the specific heat of iron at very low temperatures is considerably less than at atmospheric temperature and also the volume of gas decreases with sinking temperature, while the specific heat of gas remains fairly even, a form of filling for the cold accumulator had to be devised which takes these facts into account. Inside the cold accumulators the temperature decreases from top to bottom, also the volume of gas and the specific heat of the iron filling of the accumulator. This latter at minus 190° C. amounts only to 0,036 as compared to 0,11 at plus 20° C., that is two thirds less. The volume of gas decreases at about the same rate. The filling must, therefore, be so constituted that its mass toward the bottom or cold zone of the accumulator is greater than at the top or warmer zone and, therefore, the total flow area for the gas diminishes toward the colder end.

In the accompanying drawings, which shows a preferred embodiment of the apparatus according to the invention,

Fig. 1 is a front view of the cold accumulator with parts of the shell removed to show the filling strips of sheet metal;

Fig. 2 is a transverse section of the shell, the left side of the figure representing a

section along a line A—B of Fig. 1, the right side a section along a line C—D of Fig. 1;

Fig. 3 is a side view of two sheet metal strips one behind the other, the one in front being drawn in full lines, the rear one in dotted lines;

Fig. 4 is a top view of the same;

Fig. 5 is a side view of the same; the left side of the figure representing the front strips, the righthand side of the figure the strip lying behind, part of the front strip having been removed;

Fig. 6 shows the filling in course of manufacture.

According to the invention the strips of sheet metal are disposed inside the shell at distances apart which decrease by steps from top to bottom of the shell, as may be seen from Figs. 1 and 2, resulting in smaller spaces in the lower parts and forming narrower channels or passages appropriate to the diminishing air volume at falling temperature. The shell "a" is shown cut open in three places to expose to view the strips of sheet metal constituting the filling. In cylindrical shells the strips are disposed in spirals forming disks of from 500 to 1500 mm. diameter, as shown in Figs. 2 and 6; in square shells the strips are put in singly, in which case they must be shaped in such a way, that intervening spaces of the desired dimensions result.

To attain the highest possible effect the strips of sheet metal should be corrugated and so arranged that a brisk whirling of the air flowing through the channels formed by them is brought about. The strips may touch one another only in points, in no case along a line or plane, because the gas cannot reach places where the strips touch, so that portions of the cold-exchanging surface are thereby rendered ineffective.

With a view to minimize losses from this cause the strips are provided with corru-

66

tions running aslant towards the edges of the strips; by arranging the corrugations of neighboring strips to slant in opposite sense, the strips will touch only at the corrugations which is the desired way, i. e. there will be point contact only. The crossing of the corrugations also causes lively whirls in the gas current, thus considerably increasing the cold-exchanging effect.

10 Fig. 1 shows the shell cut open in three places to expose the filling to view; on the left-hand side the front strip is seen, while at the right is shown the strip which lies behind. The corrugations of the upper 15 strips "b" and "c" are higher than those of the middle strips "d" and "e" and of the lowest "f" and "g," as seen in Figs. 1 and 2.

Fig. 2 shows the filling of a cylindrical cold accumulator in transverse section. In 20 this spirally wound filling two strips with corrugations slanting in opposite sense are always wound simultaneously, thus forming a double-wormed spiral with corrugations lying crossways. This is seen very plainly 25 in Fig. 6 which shows the spiral winding in course of manufacture, that is in the unfinished state. The strips "d" and "e" are preliminarily drawn through pairs of furrowed rollers "h" and "i," and "k" and "l," 30 to corrugate them. The strips are laid next to one another and then spirally wound around the axle "m" of the cold accumulator "a".

The accumulator described above is of 35 particular advantage in the regenerative refrigeration of gases for the purpose either of separating the components of a mixture of gases, or of removing the moisture or carbon dioxide therefrom. In such case, at 40 least two cold accumulators of the type shown in Fig. 1 must be present. At the beginning of the process employing the above-described accumulator, the metallic strips comprising the filling or packing of 45 the accumulator are cooled by means of a refrigerating machine to the temperature at which the particular gas mixture being treated, for example, air, is to be separated into its components, or at which water vapor or carbon dioxide will precipitate from 50 air or any other gas. The air or other gas is then introduced at the top of the first accumulator, which at this stage of the process acts as a cold exchanger, and which 55 gives up its cold to such air and cools the same to the desired temperature. After that the air is separated into its components, or water vapor or carbon dioxide is precipitated in a suitable apparatus, after which 60 the cold components or the cold gas is fed to a second accumulator from the bottom to the top thereof. This second accumulator now operates to store in its packing the cold of the discharging components or gas; 65 in effect, the cold of the first accumulator is

in this manner transferred to the packing of the second accumulator. The components or gases escaping from the second accumulator are almost as warm as the gas introduced into the first accumulator.

70 After about five minutes, the flow of gas is reversed, and the gas to be treated is fed first through the second accumulator and passed out through the first accumulator, so that it is cooled in the second and gives up its cold to the first accumulator. After about five minutes the operation is again reversed and the gas to be treated is again introduced into the first accumulator. The 75 accumulator described above thus operates alternately as cold accumulator and cold exchanger in a regenerative refrigerating system, and is to be distinguished from the known forms of tubular cold exchangers 80 which operate continuously.

85 I claim:

1. A cold accumulator comprising a shell, the inside space of such shell being divided into a number of zones, strips of sheet metal disposed in each of said zones and adapted to be chilled by a stream of cold gas passing through the accumulator and to cool a subsequent stream of warmer gas, said strips disposed in such a way that from zone to zone the extent of their surface and the mass 90 of metal toward the colder end become greater, while the total flow area of the gas channels becomes smaller.

2. A cold accumulator comprising a shell, an axle in said shell, the inside space of 100 said shell being divided into a number of zones, disks composed of two parallel strips of sheet metal adapted to be chilled by a stream of cold gas passing through the accumulator and to cool a subsequent stream 105 of warmer gas, said strips being wound spirally around the axle of the shell in each of said zones, and being provided with corrugations aslant to the direction of the gas current, the corrugations of each pair of 110 said strips lying crossways.

3. A cold accumulator comprising a cylindrical shell, an axle in said shell, the inside space of said shell being divided into a number of zones lying below one another, 115 disks composed of two parallel strips of sheet metal adapted to be chilled by a stream of cold gas passing through the accumulator and to cool a subsequent stream of warmer gas, said strips being wound spirally around the axle of the shell in each of said zones, and provided with corrugations aslant to the direction of the gas current, the corrugations of each pair of 120 said strips lying crossways.

4. A cold accumulator comprising a shell, an axle in said shell, the inside space of said shell being divided into a number of zones, two parallel strips of sheet metal adapted 125 to be chilled by a stream of cold gas pass-

ing through the accumulator and to cool a subsequent stream of warmer gas, said strips being disposed spirally around the axle of the shell in each of said zones, and provided with corrugations aslant to the direction of the gas current, the corrugations of each pair of said strips lying cross-ways, the height of said corrugations decreasing step by step towards the colder end of the accumulator.

10 In testimony whereof I have affixed my signature.

MATHIAS FRÄNKEL.
